UNITED STATES PATENT OFFICE.

IRVING W. BLANCHARD, OF BEVERLY, MASSACHUSETTS, ASSIGNOR TO UNITED SHOE MACHINERY COMPANY, OF PATERSON, NEW JERSEY, A CORPORATION OF NEW JERSEY.

MACHINE FOR FORMING UPERS OF BOOTS AND SHOES.

1,161,019.

Specification of Letters Patent. Patented Nov. 23, 1915.

Application filed February 13, 1914. Serial No. 818,595.

To all whom it may concern:

Be it known that I, IRVING W. BLANCHARD, a citizen of the United States, residing at Beverly, in the county of Essex and State of Massachusetts, have invented certain Improvements in Machines for Forming Uppers of Boots and Shoes, of which the following description, in connection with the accompanying drawings, is a specification, 10 like reference characters on the drawings indicating like parts in the several figures.

This invention relates to apparatus for shaping the uppers of boots and shoes.

The invention is herein disclosed as embodied in a machine for use in the manufacture of that class of shoes commonly known to the trade as "stitch-downs," in which the upper is provided with an out-turned flange to receive the stitches or other fastenings by 20 which the upper is secured to the sole, but it will be apparent that many of the novel features of construction and principles of operation are applicable to the manufacture of shoes of other types.

According to a preferred practice in the manufacture of stitch-down shoes, the upper, before its attachment to the sole, is subjected to a forming or molding operation in which the sole attaching flange is shaped to 30 lie about the toe portion and the toe is given the shape desired for the finished shoe. A

method of preparing an upper in this manner forms the subject matter of United States Letters Patent No. 947,895, granted to Karl Engel Feb. 1, 1910, and a machine by the use of which such a method may be practised is disclosed in United States Letters Patent No. 998,682 granted to Karl Engel July 25, 1911. According to the practice disclosed in these patents, the marginal portion of the upper blank at the toe end is first clamped between members that confine the margin during the toe forming operation and impart the pressure necessary to

40 form the out-turned flange, and the unconfined portion of the blank is then operated upon by a toe former that curves the blank to the shape of the toe of the finished shoe and is moved to cause the toe to project somewhat over the out-turned flange. It 45 will be obvious that in this toe forming operation, unless the blank may be so adjusted as to provide the unconfined portion with the requisite fullness, the clamped mar-

ginal portion will be subjected to strains to 55 compensate for the excess of material required for the curved shape of the toe, and in view of the further fact that some portions of the toe, as for example the abruptly curved end, require a relatively greater 60 amount of material than other portions, the strains upon different portions of the margin will differ both in direction and in degree. In order to avoid unduly straining or tearing the blank it is necessary, therefore, 65 to provide for some distribution or adjustment of the material to meet the demands of the operation of the toe former. In the practice set forth in the patents above mentioned, accordingly, provision is made for 70 suitable compensating movement of the flange portion of the blank during the toe forming operation.

An object of this invention is to provide 75 mechanism of improved construction and mode of operation for forming or shaping shoe uppers, especially at the forepart or toe portions, by the use of which the blank may be shaped with accuracy and uniformity and the material distributed with 80 great precision to meet the demands of the toe forming operation, so that a smooth toe of the desired shape may be formed without subjecting portions of the blank to excessive strains.

85 A feature of the invention accordingly resides in novel means for moving portions of a blank to provide the requisite amount of material to be used for forming the toe and to meet the varying demands of the toe 90 forming operation at different portions of the blank. As preferably constructed, such means comprises suitably operated mechanism for effecting compensating movement of the flange or marginal portion of the 95 blank in the general direction of the body of the blank, such movement being completed before the completion of the toe forming operation and particularly before the final shaping of the abruptly curved portions of the toe at the toe end of the blank. With this arrangement the marginal portion of the material is preferably gathered and moved inwardly at the toe end and held during the operation of a former which 100 shapes this end portion of the blank and is preferably moved to cause the end of the toe to bulge over the confined marginal por-

tion. During the operation of shaping the forward end portion of a toe blank it has been found advantageous to restrain the rear portion of the blank between the opposite sides from longitudinal forward movement so as to prevent distortion of the blank, and means for effecting such control of the blank constitutes a further feature of the invention.

10 Another feature of the invention consists in means for forming or shaping successively different portions of a blank of sheet material, herein shown as comprising means for forming first the rear portion of a toe blank and for forming subsequently the toe end of the blank.

15 A further feature consists in a novel former having parts which are movable relatively to shape different portions of a blank.

20 The illustrated embodiment of the invention comprises a toe former made up of relatively movable portions constituting in effect two formers which are operated successively to form different portions of the blank, the former for the rear portion of the blank having its forming movement imparted thereto before the former which operates at the toe end becomes effective to shape the blank, and preferably assisting in restraining the rear portion of the blank from longitudinal forward movement during the operation of the toe end former.

25 A feature of the invention is to be recognized also in provision for movement of a toe end former forwardly in a predetermined path oblique to the plane of the confined blank margin to form the end portion of the toe.

30 35 A further feature is a simple form and arrangement of operating mechanism for effecting the required movements of the distributing, clamping and toe forming means.

40 45 Still other features are to be recognized in novel means for gaging the width of the out-turned flange upon the blank, and provisions for adjustment of the various parts to vary the width of the flange, the extent of gathering movement imparted to the blank, and the effect of the toe forming means upon the blank, and to adapt the mechanism for operation upon blanks of different sizes.

50 55 The above and other features of the invention, including certain details of construction and combinations of parts, will now be described with reference to the accompanying drawings and pointed out in the claims.

60 65 The invention is illustrated as embodied in a machine of the general type disclosed in the pending application of Karl Engel and Louis M. Brown, Ser. No. 464,559, filed Nov. 27, 1908. Machines of this type comprise mechanism for shaping the toe and

heel portions of upper blanks, but only such portions of the complete mechanism as are directly related to the features of the present invention will be described herein.

70 It should be understood also that the invention is not limited in its application to this particular machine but is susceptible of various embodiments.

75 In the drawings, Figure 1 is a vertical section through a machine of the type above referred to with the present invention embodied therein, Fig. 2 is a perspective view of a detached portion of the mechanism for operating upon the forepart of an upper, Fig. 3 is a vertical central section through the mechanism shown in Fig. 2, Fig. 4 is a view showing in disassembled relation the parts of the novel toe former and mechanism associated therewith, Fig. 5 is a fragmentary view, partly in section, of the shaping mechanism for the forepart of an upper, showing a blank in position to be operated upon, Fig. 6 is a view similar to Fig. 5, showing the positions of the various parts at the end of the toe forming operation, Fig. 7 is a plan view of the lower clamp member, and Fig. 8 is a fragmentary view of a portion of the lower clamp member and the parts associated therewith in disassembled relation.

90 95 The complete machine, as described in the pending application above referred to, is preferably provided with two upper forming mechanisms, one for forming the upper of a right shoe and the other for forming the upper of a left shoe. Since these mechanisms both comprise the same parts, only that mechanism which is intended for use in forming the upper of a right shoe is shown and will be described herein in detail.

100 105 The upper forming mechanisms are inclined to the horizontal substantially on an angle of 45° and, as previously stated, comprise means for forming the heel portion of the upper and means for shaping the forepart of the upper, these means being arranged to operate in succession. The mechanism for operating upon the forepart is carried by a slide 2 which is movable up and down the incline of the frame 4. This slide, it will be understood, is connected with means for operating upon the heel portion of the blank and during the latter part of the heel forming operation is moved downwardly by means not illustrated herein in detail but fully described in the pending application above mentioned, thereby bringing the mechanism for shaping the forepart into position to receive this part of the blank from which the toe is to be formed.

110 115 120 125 A portion of the mechanism for operating upon the forepart of the upper is supported by a pair of guides 6 upon the frame 4, and includes two clamp members 8 and 10, of which the upper clamp member 8 is

mounted to slide in longitudinal grooves in the guides 6. The lower clamp member 10 is supported on the headed ends of bolts 12 which pass therethrough and through the member 8, and is drawn normally into clamping relation to the member 8 by springs 14 which surround the bolts above the member 8 and engage nuts upon the upper ends of the bolts. The clamp members 8 and 10 are constructed and arranged to clamp a marginal portion of the toe part of the upper and to form an out-turned flange thereon, the member 10 being moved downward in opposition to the force of the springs 14 to permit the introduction of the blank by means which will be hereinafter described. Both clamp members are formed with substantially plane material engaging faces, and the lower clamp member is provided with a plurality of grooves 16 that radiate outwardly from the central cut-away portion of the member and are formed to retain and guide a plurality of slides 18 which are arranged to engage the under surface of the marginal portion of the blank at and near the toe end, and similar but wider slides 20 for engaging the marginal portion at the sides of the blank. The slides 20, it will be noted, are seated also in depressions 22 in the member 10 and are cut away to embrace the bolts 12. The slides 18 and 20 have roughened or toothed material engaging faces which project slightly above the plane face of the member 10 so as to secure an effective hold upon the material. In operation the slides are moved inwardly in the guideways to effect the required distribution of the material of the blank to meet the demands of the toe former. It will be seen by reference to Fig. 7 that the slides are arranged unsymmetrically with respect to the member 10 in view of the unsymmetrical form of an upper blank. The parts illustrated are arranged for operating upon the upper of a right shoe; and for operating upon a left blank it will be understood that the grooves and slides are to be disposed reversely with respect to the opposite sides of the clamp member.

The slides 18 and 20 are controlled and are moved in their guideways by mechanism which includes rods 24 the lower end portions of which are shaped to engage in slots 26 in the slides. The rods extend through the upper clamp member 8 and are flattened to engage in guiding slots 28 in this member, this construction providing shouldered portions on the rods which rest upon the upper surface of the member 8 and thus restrain the rods from further downward movement through said member. The forward edges of the flattened portions of the rods are curved to correspond to the transverse curve of the front portion of the member 8, and are shaped to provide projections

30 the lower faces of which form continuations of the clamping face of the member 8. The slots 28 are of sufficient length to permit the required operative movement of the rods 24, with sufficient leeway to provide for adjustment of the extent of such movement. The rod ends engage deeply enough in the slides to avoid disengagement therefrom when the clamp member 10 is at its lower limit of movement, and are thus in position to act as gages to position the margin of the material when the blank is inserted in the mechanism.

The rods 24 are inclined to the planes of the clamp members and extend upwardly and outwardly substantially in the planes of the slots 16. This arrangement of the rods is fixed by a block 32 through which the rods extend in sliding relation. The rods are restrained substantially from upward movement by engagement with the surface of a plate 34 which is supported in spaced relation to the clamp member 8 by posts 36. These posts are secured to the member 8 and are shouldered at their upper ends to receive the plate 34 which is confined thereon by nuts 38. The posts 36 are substantially perpendicular to the plane of the member 8, and extend through the block 32 which is arranged to slide thereon in the space between the members 8 and 34. This movement of the block upon the fixed posts 36 will, it is evident, cause the rods 24 to move laterally in directions parallel to the plane of the member 8 while maintaining the angular relation of the rods to the clamp members and to one another, an upward movement of the block causing the rods to move inwardly toward the cut-away portions of the clamp members and to impart a similar movement to the slides 18 and 20. The extent of movement of the rods and slides for a given movement of the block 32 will, it is evident, depend upon the degree of inclination of the rods to the plane of the member 8, and by fixing different rods at different inclinations corresponding slides may be moved through different respective distances. Such an arrangement is within the province of the invention, although in the illustrated preferred embodiment the rods and slides are arranged for movements substantially equal in extent. The block is moved upwardly by mechanism which will be subsequently described and is returned preferably by gravity to impart outward movement to the slides after the completion of the forming operation.

Mounted upon the bolts 12 at the rear of the clamp member 8 and pressed downwardly against the member 8 by the springs 14 is a bridge piece 40 the purpose of which will hereinafter appear. A bar 42 is secured at the rear of the clamp member 10 and has adjustably mounted thereon gages

44 to position the side edges of the blank as the latter is inserted between the clamp members. Between the gages and the bar are plates 46 which serve to raise the edges 5 of the material sufficiently to clear adjacent portions of the clamp member when the blank is inserted. The member 10 is also provided with stripping devices which comprise metal springs 48 seated in recesses 10 in the clamp member between the slots 16 and extending normally slightly above the plane of the toothed faces of the slides 18 and 20 so as to facilitate the insertion of the blank and disengagement of the blank from the teeth on the slides when the clamp members are separated after the completion of the forming operation.

The mechanism described thus far is operated and controlled through members that 20 are carried by a slide 50 which is moved in directions substantially perpendicular to the planes of the clamp members and supports also means for forming the unconfined portions of the blank after the margin of the latter has been clamped. The slide 50 carries a roll 52 that enters a cam groove 54 in a cam disk 56 on a cam shaft 58, which is suitably rotated in the direction of the arrow shown on Fig. 1, and is forked at its lower end to embrace the cam shaft by which its movements are partly guided.

Carried by the slide 50 and guided in grooves 60 therein for movement in directions at right angles to the directions of movement of the slide is a slide 62 which carries at one end a plate 64 that engages in grooves in the member 2 so that the slide 62 may be moved transversely of said member on the upward and downward movements of the slide 50 and shares the longitudinal movements of the member 2 up and down the incline of the frame independently of the slide 50. The slide 62 supports and guides for sliding movement with respect thereto two other slides 66 and 68, of which the slide 66 is formed with side flanges that are retained in grooves 70 in the member 62, the direction of these grooves being such that the member 66 may be adjusted in directions parallel to the grooves 60 in the member 50. The slide 66 is formed with a projection 72 which is grooved at its edges to embrace retaining flanges that are formed at opposite ends of a recess in one side of the bar 42. This arrangement permits the member 72 to slide transversely of the bar but serves to fix the longitudinal position of this member and of the slide 66 with reference to the clamp members. Secured to 60 the member 72 is a transverse bar 74 the ends of which are positioned to project over and engage ears 76 on the clamp member 10. With this arrangement it will be seen that when the slide 50 is moved downwardly the

slides 62 and 66 will be carried therewith 65 and the bar 74 will pull downwardly upon the ears 76 and separate the lower clamp member 10 from the member 8 in opposition to the force of the springs 14.

The slide 66 also carries a rod 78 which is 70 threaded into the slide at one end and projects upwardly through holes in the clamp members 10 and 8 in position to engage, when the slide 50 is moved upward, a plug 80 which is adjustably threaded into a recess 75 in the block 32. By this means upward movement of the slide 50, which serves, as will be evident from the preceding description, to release the clamp member 10 and permit the springs 14 to move this member 80 into clamping relation to the member 8, also effects upward movement of the block 32 with consequent movement of the slides 18 and 20 inwardly toward the cut-away portion of the clamp. The parts are preferably 85 so adjusted that the member 10 is first moved to clamping position and the rod 78 then engages the plug 80 to effect the gathering and compensating movement of the marginal portion of the blank which is engaged by the 90 slides and the clamp members. Adjustment of the plug 80 will vary the time at which the upward movement of the block 32 is to begin and consequently the extent of movement thereof and of the slides 18 and 20. 95 The lower limit of movement of the block 32 is determined by a screw 82 which is threaded into a bore in the block and slides freely through the plate 34, the head of the screw limiting the downward movement of 100 the block by contact with the plate. Adjustment of the screw 82, it will be evident, varies the initial position of the block and consequently the positions of the rods 24 and 105 of the blank engaging slides 18 and 20 in their guideways. If the block is adjusted downwardly this serves to retract the rods and slides from the central portion of the clamp and permits the introduction of a larger blank. Such adjustment would also 110 serve, of course, to vary the time and extent of movement imparted to the block from the rod 78, but these conditions may be regulated independently by adjustment of the screw 80. The bores which receive the 115 screws 80 and 82 are in alinement, so that if the screw 82 is removed a tool may be inserted to adjust the screw 80 as desired, and the latter is held preferably in adjusted position by a set screw 81.

The slide 62 is provided also with grooves 84 which are inclined to the direction of the grooves 70 as clearly shown in Figs. 1 and 3, and in these grooves are seated flanges 86 on the slide 68. The slide 68 is bored to permit 125 the passage of the rod 78 which thus prevents relative longitudinal movement of the slides 66 and 68, and such movement is also

prevented by a screw 88 which is threaded into an upward projection of the slide 68 and extends through an elongated slot 90 in the member 72 with its head in engagement with said member. The rod 78 and the slot 90, however, permit the slide 68 to move upward or downward to a limited extent with reference to the slide 66, which movement is caused by reason of the angular relation of the grooves 70 and 84 when both slides are moved together longitudinally with the clamp members for the purpose of adjustment, as will be subsequently explained.

The slide 68 supports adjustably at its upper end the rear portion 92 of a toe former for use in shaping the unconfined portion of the toe blank. The forward portion 94 of the toe former, which is the part that is used to shape the toe end of the blank, is mounted 20 adjustably upon a slide 96 which has flanges 98 that engage in grooves 100 formed in the slide 68, and extend upward on a considerable incline toward the clamp members. The slide 96 has an elongated slot 102 to receive the rod 78, which permits the slide to move in the grooves 100 with reference to the rod and to the slide 68.

It will now be seen that when the member 50 receives its upward movement it carries 30 with it the toe former, and after the marginal portion of the blank has been clamped and while the slides 18 and 20 are operating to gather and adjust different portions of the blank, the part 92 of the former operates 35 to shape the unconfined portion of the blank between the sides of the clamp at a distance from the toe end. The former 92 at the end of its upward movement finally presses the material of the blank against the bridge 40 piece 40, particularly at points near the sides of the former, to prevent forward movement of this portion of the material during the subsequent formation of the toe end.

At the end of the upward movement of the member 50 the unconfined portions of the blank in front of the part 92 of the former are in a somewhat loose and unshaped condition, not having as yet been operated upon to any effective extent by the 45 toe end former 94. To form the toe end of the blank, movement is now imparted to the slide 96 on the angle determined by the grooves 100, and this carries the former 94 forwardly and upwardly in a path inclined to the plane of the clamp members and over the curved edge of the upper clamp member 8 to the position shown in Fig. 6. For effecting this movement the slide 96 is provided with a block 104 which is flanged 50 to engage in grooves in a block 106 adjustably connected by a rod 108 to a toggle actuated member 110, the adjustable connections between the rod and member comprising a threaded sleeve 112 upon a shoul-

dered portion of which the member 110 65 is confined by a nut 114, said sleeve having turning movement imparted thereto when desired by a gear 116 intermeshing with a second gear 118 on a shaft 120, this shaft being restrained from longitudinal movement in a bearing formed in an upstanding lug 122 on the slide 2. The sleeve 112 is freely movable through the lug 122, and the member 110 is pivotally connected to one link 124 of a toggle, the other link 126 70 75 of which is connected to the member 2.

The toggle is straightened and broken to effect movement of the rod 108 and the slide 96 by a link 128 connected at one end to the knee joint of the toggle and at its other end to a fulcrum link 130 upon a bracket 132 on the slide 2, whereby the link 130 is caused to travel with the slide in its movements, the link 128 being provided at its juncture with the fulcrum link with a pin 85 134 which enters a slot in an offset arm 136 of a toggle operating slide 138. This slide is forked at its lower end to embrace a cam shaft 140 which is rotated in the direction of the arrow in unison with the shaft 58, 90 and is suitably guided at its upper end by the frame. The slide 138 is reciprocated to effect its toggle straightening and breaking operations by the engagement of a cam roll 142 on the slide with a cam groove 144 95 in a cam disk 146 carried by the shaft 140.

The extent of movement of the toe and former caused by the straightening of the toggle 124, 126 and particularly the limit of return movement of this former, may be 100 varied by turning the nut 114 upon the sleeve 112 so as to provide lost motion between the member 110 and the sleeve. The initial position of the slide 96 with reference to the slide 68, and therefore of the 105 former 94 with reference to the former 92 and the clamp members, may be likewise varied by turning the sleeve 112 alone, this adjustment serving to vary also the limit of forward movement of the toe end former. 110 The shaft 120, however, is threaded into an extension of the clamp member 8 which, as previously stated, is mounted for sliding movement in the guides 6, and since the clamp members 8 and 10 and the slides 66 115 and 68 are all secured together for movement up and down the incline of the machine frame, it will be clear that turning of the shaft 120 by means of the hand wheel 148 will adjust these parts longitudinally 120 with reference to the slide 2 and the heel forming mechanism, the purpose of this adjustment being to adapt the machine to operate upon uppers of different sizes. During this adjusting movement the slides 66 and 125 68 will move relatively to the slide 62 which is restrained from longitudinal movement with reference to the slide 2 as previously

explained, and in view of the angular relation of the grooves 70 and 84 the slide 68 will have a relative upward or downward movement on the slide 66 to adjust 5 proportionately the initial position of the former 92 for different sizes of upper. The threads upon the shaft 120, moreover, are of the same pitch as those upon the rod 108, and the gears 116 and 118 have 10 the same number of teeth, so that when the shaft 120 and the sleeve 112 are turned together there will be no relative adjusting movement longitudinally between the slides 68 and 96 and between the parts of the toe 15 former.

When it is desired to adjust the position of the toe and former 94 with reference to the clamp members and to the former 92 to vary relatively the limit of forward movement of the former 94, the gear 118 may be disconnected from the shaft 120 and be moved along the shaft out of engagement with the gear 116, so that the sleeve 112 may be turned without turning the shaft 120. 20 This adjustment will serve to vary the bulge of the toe over its flange and also to vary the amount of longitudinal stretch imparted to the blank. When the slide 2 moves upward or downward in the operation of the 25 machine it will be understood that the slide 62 and all parts of the mechanism for operating upon the forward or toe portion of the upper blank are carried therewith without relative movement of any portions of 30 this mechanism.

In the operation of the machine, assuming that the several adjustments have been made in the manner previously explained, it will be understood that after the heel 40 portion of the upper has been formed and while it is still retained in the forming mechanism the parts come to rest with the mechanism for operating upon the toe part in position to receive the toe end of the 45 upper, and with the cams shown on Fig. 1 somewhat advanced from the positions indicated on said figure. The clamp member 10 at this time is held in its lowermost position by engagement of the bar 74 with the 50 ears 76. The forepart of the upper is now inserted between the clamp members with its margin in engagement with the lower end portions of the rods 24, as shown in Fig. 5, and the machine is again started 55 in operation by depression of its actuating treadle. As the cam shafts 58 and 140 resume their rotation, the cam 54 first operates upon the roller 52 to impart upward movement to the slide 50 and the mechanism 60 supported thereby. The first effect of this operation is to release the lower clamp member 10 and permit the springs 14 to move this member upwardly to clamp the marginal portion of the blank between the

opposed faces of the clamp members. The head of the rod 78 next encounters the plug 80 and imparts upward movement to the block 32, which causes the rods 24 and the slides 18 and 20 to move inwardly toward the body portion of the blank. During this movement of the block the slides, by means of their toothed faces, impart inward movement to the marginal portion of the blank to adjust the material and provide the proper fullness to meet the demands of the toe former, and by reason of their relative arrangement cause a gathering of the material of the blank along the flange line. At the same time the two portions 70 95 90 85 80 75 70 65 60 55 50 45 40 35 30 25 20 15 10 5 0 of the toe former are moving upward, and the portion 92 becomes effective to stretch and form the material at the rear portion of the blank and finally to clamp the material at the sides of the former, and it may be also upon the top 85 80 75 70 65 60 55 50 45 40 35 30 25 20 15 10 5 0 of the former, against portions of the member 40. Upward movement of the slide 50 now ceases by reason of the fact that the roll 52 reaches the concentric portion of the offset of the cam groove 54, and as the cam 90 85 80 75 70 65 60 55 50 45 40 35 30 25 20 15 10 5 0 shafts continue their rotation the roll 142 is operated upon by the offset of the cam groove 144 to move the slide 138 upwardly. This causes the toggle 124, 126 to be straightened and imparts, as previously explained, movement to the toe end former 94 to the position shown in Fig. 6, so as to form the blank at the toe end with a bulge 95 90 85 80 75 70 65 60 55 50 45 40 35 30 25 20 15 10 5 0 projecting over the clamped flange.

Rotation of the shafts 58 and 140 now 100 ceases automatically, as explained in the pending application previously referred to, and the parts of the mechanism are retained in the positions to which they have been moved to permit the upper to set to 105 shape while the upper of the other shoe of a pair is being operated upon in another part of the machine. When it is desired to remove the upper, a further actuation of the starting mechanism, it will be understood, causes the parts to return to their first position represented in Fig. 1. In this movement the cam shafts continue their forward rotation, and the toe end former 94 is first returned by downward movement of the slide 138, after which the slide 50 is moved downward. Although the rod 78 will begin its downward movement before the bar 74 reaches a position to contact with the ears 76 on the lower clamp 110 member, the weight of the block 32 is not sufficient to cause the block to move downwardly until the material has been released by the clamp members, because of the engagement of the teeth on the slides 18 and 20 with the blank. As the clamp members separate, moreover, the springs 48 115 110 105 100 95 90 85 80 75 70 65 60 55 50 45 40 35 30 25 20 15 10 5 0 serve to strip the material from the teeth 120 115 110 105 100 95 90 85 80 75 70 65 60 55 50 45 40 35 30 25 20 15 10 5 0 125

so that the slides may move back freely without injuring the material. Subsequently the heel portion of the upper is released and the machine comes to rest with 5 the parts in the position shown in Fig. 1.

The term "blank" or "toe blank" used in the claims is to be understood as referring generally to materials such, for example, as the forepart of an assembled shoe upper, 10 adapted for use in forming the toe portion of a boot or shoe or for forming other like articles of manufacture.

Although the invention is disclosed as embodied in apparatus having the specific features of construction shown and described, 15 it will be understood that the invention is not thus limited in its application but that other embodiments are comprehended within the spirit and scope thereof as defined in the claims.

Having described the invention, what I claim as new and desire to secure by Letters Patent of the United States is:—

1. In apparatus of the class described, the 25 combination with means for forming a toe from a toe blank, of means for effecting relative movement of adjustment of different portions of the blank at its edge in directions converging toward the body of the 30 blank, said adjusting means being arranged to operate before the operation of said forming means to shape the toe end of the blank.

2. In apparatus of the class described, the 35 combination with means for forming a toe from a toe blank, of means for imparting adjusting movement to the marginal portion of the blank at the toe end in the direction of the body of the blank, said adjusting means being arranged to operate before the toe end of the blank is shaped by 40 said forming means.

3. In apparatus of the class described, the 45 combination with a toe former, of means for gaging the position of a blank with reference to said former, means for moving the marginal portion at the toe end of the blank rearwardly, and means for subsequently moving the toe former forwardly.

50 4. In apparatus of the class described, the combination with means for forming a toe from a toe blank, of means for clamping the marginal portion of the blank to form a flange thereon, said means including portions movable while in clamping position in the plane of said means, means for operating said portions of the clamping means to move the flange in the direction of the body of the blank, and means for subsequently 55 operating the forming means to shape the toe end of the blank.

5. In apparatus of the class described, the combination with means for confining the marginal portion of a toe blank, of means

for shaping the rear portion of the blank, 65 and means for subsequently shaping the toe end of the blank.

6. In apparatus of the class described, the combination with means for confining the marginal portion of a toe blank, of means 70 for shaping the rear portion of the blank, means operated simultaneously with said shaping means to adjust relatively different parts of the confined marginal portion of the blank, and means for subsequently shaping 75 the toe end of the blank.

7. In apparatus of the class described, the combination with means for forming a toe from a toe blank, of means for restraining the rear portion of the blank from longitudinal forward movement during the operation of said forming means at the toe end of the blank.

8. In apparatus of the class described, the combination with means for confining the 85 marginal portion of a toe blank, of means for shaping the rear portion of the blank and for confining said portion against longitudinal forward movement, and means for subsequently shaping the toe end of the 90 blank.

9. In apparatus of the class described, the combination with means for clamping the marginal portion of a toe blank, of a former for shaping the rear portion of the blank 95 movable in a direction transverse to the plane of said clamping means, and a former for shaping the toe end of the blank movable relatively to said rear former.

10. In apparatus of the class described, 100 the combination with means for clamping the marginal portion of a toe blank, of a former for shaping the rear portion of the blank movable in a direction transverse to the plane of said clamping means, a former 105 for shaping the toe end of the blank, means for moving both said formers together in a direction transverse to the plane of said clamping means, and means for moving the toe end former relatively to said rear former 110 to shape the toe end of the blank.

11. In apparatus of the class described, the combination with means for clamping the marginal portion of a toe blank, of a former for shaping the rear portion of the 115 blank movable in a direction transverse to the plane of said clamping means, a former for shaping the toe end of the blank, means for moving both said formers together in a direction transverse to the plane of said 120 clamping means, and means for moving the toe end former relatively to said rear former in a direction oblique to the plane of said clamping means to shape the toe end of the blank.

12. In apparatus of the class described, a former for shaping the rear portion of a toe blank, means for confining the blank

- against said former to prevent longitudinal forward movement of the rear portion of the blank, and a former for shaping the toe end of the blank movable forwardly from 5 said rear former.
13. In apparatus of the class described, the combination with means for clamping the marginal portion of a toe blank, of a former movable forwardly toward the toe 10 end of the blank, and means for effecting said movement of the former constructed to insure movement thereof in a predetermined path oblique to the plane of said clamping means.
14. In apparatus for shaping sheet material, a former comprising relatively movable parts, and means for operating said parts of the former successively to shape different portions of the material.
15. In apparatus for shaping sheet material, a former comprising relatively movable parts, means for effecting relative movement of said parts to shape different portions of the material, and means for varying the extent of relative movement of said parts of the former.
16. In apparatus for forming a toe from a toe blank, a former for shaping the rear portion of the blank, and a second former for 30 shaping the toe end of the blank, said formers being relatively movable, and said apparatus including provision for adjustment to vary the initial relative positions of said formers.
17. In apparatus for forming a toe from a toe blank, a former for shaping the rear portion of the blank, a former movable forwardly from said rear former to shape the toe end of the blank, means for imparting 40 forward movement to said toe end former, and means for varying the limit of forward movement thereof.
18. A machine of the class described comprising a frame, clamp members arranged 45 for longitudinal adjusting movement upon the frame, a former adjustable transversely to the plane of said members, and means for effecting said adjusting movement of the former simultaneously with the adjusting movement of said members.
19. A machine of the class described comprising a frame, clamp members arranged for longitudinal adjusting movement upon the frame, a former, a slide supporting said former and movable longitudinally with the clamp members, and means for effecting movement of said slide in a direction transverse to the planes of the clamp members simultaneously with the adjusting movement 55 of said members.
20. In apparatus for forming a toe from a toe blank, a former for shaping the rear portion of the blank, a support for said former, said support being formed with 60 grooves inclined upwardly and forwardly in a direction oblique to the planes of the clamp members, a slide having flanges seated in said grooves, and a toe end former mounted on said slide.
21. In apparatus for forming a toe from a toe blank, a pair of clamp members relatively movable to confine the marginal portion of the blank, resilient means for moving said members relatively to clamping position, and means for separating said members to receive the blank. 70
22. In apparatus for forming a toe from a toe blank, a pair of clamp members relatively movable to confine the marginal portion of the blank, resilient means for moving said members relatively to clamping position, an operating member movable in directions transverse to the planes of said clamp members and having means for engaging the lower clamp member, and means for moving said operating member in a direction to separate the clamp members to permit the introduction of the blank. 80
23. In apparatus for forming a toe from a toe blank, clamp members arranged to confine the marginal portion of the blank, and adjustable gages located rearwardly of said members for guiding the edges of the blank when the blank is inserted between the clamp members. 90
24. In apparatus of the class described, the combination with means for forming a toe from a toe blank, of clamp members for confining the marginal portion of the blank, one of said members including blank engaging portions movable relatively to other portions thereof in directions converging toward the body of the blank. 100
25. In apparatus for forming a toe from a toe blank, clamp members arranged to clamp the marginal portion of the blank, one of said members having guideways formed therein converging toward the body portion of the blank, and slides movable in said guideways formed to engage the surface of the marginal portion of the blank at one side. 105
26. In apparatus of the class described, clamp members relatively movable to clamp a piece of material, one of said members including material engaging slides relatively movable thereon in the plane of the clamping face of said member in directions converging toward the body of the material, and operating means engaging said slides to 110 impart movement thereto.
27. In apparatus of the class described, clamp members relatively movable to clamp a piece of material, one of said members including material engaging slides relatively 120 movable thereon in the plane of the clamping face of said member, said slides having slots formed therein, and operating means engaging in said slots for imparting movement to the slides. 130

28. In apparatus of the class described, clamp members relatively movable to clamp the marginal portion of a blank, one of said members including blank engaging slides 5 relatively movable thereon in the plane of the clamping face of said member, and operating means for imparting movement to said slides, said operating means including portions located to gage the position of the 10 margin of the blank.

29. In apparatus of the class described, clamp members relatively movable to clamp the marginal portion of a blank, one of said members including blank engaging slides 15 relatively movable thereon, operating means for moving said slides from an initial position inwardly toward the body of the blank and including portions located to gage the position of the margin of the blank, and 20 means for varying the initial position of said slides and gaging means with reference to the clamp member.

30. In apparatus of the class described, clamp members relatively movable to clamp 25 a piece of material, one of said members including slides arranged to engage the surface of the material, and operating means for said slides comprising rods engaging the slides at one end, and means for imparting 30 lateral movement to the rods to move the slides.

31. In apparatus of the class described, clamp members relatively movable to clamp 35 a piece of material, one of said members including slides arranged to engage the surface of the material, and operating means for said slides comprising rods engaging the slides at one end and extending in angular 40 relation to the planes of said clamp members, means for restraining the rods from endwise movement, and means movable in 45 engagement with said rods in directions forming a different angle than the rods with the planes of the clamp members for imparting lateral movement to the rods to move the slides.

32. In apparatus of the class described, clamp members relatively movable to clamp the marginal portion of a toe blank, one of 50 said members including toothed slides arranged to engage the surface of the blank and movable in paths that converge in the direction of the blank, operating rods engaging at one end with said slides and extending in divergent directions inclined to the planes of said clamp members, means for restraining the rods from endwise movement, and an operating member movable in 55 sliding engagement with the rods in directions substantially perpendicular to the planes of the clamp members to effect lateral movement of the rods.

33. In apparatus of the class described, clamp members relatively movable to clamp 60 the marginal portion of a toe blank, one of

said members including slides arranged to engage the surface of the blank and movable in directions toward and from the body of the blank, and operating means for said slides comprising rods engaging the slides 70 at one end, and a guide member through which said rods extend in directions inclined to the planes of the clamp members, said guide member being movable in sliding engagement with the rods in directions substantially perpendicular to the planes of the 75 clamp members to effect movement of the rods and the slides toward and from the body of the blank.

34. In apparatus of the class described, 80 clamp members relatively movable to clamp the marginal portion of a toe blank, one of said members including slides arranged to engage the surface of the blank and movable in directions toward and from the body of 85 the blank, and operating means for said slides comprising rods engaging the slides at one end, and a guide member through which said rods extend in directions inclined to the planes of the clamp members, 90 said guide member being movable in sliding engagement with the rods in directions substantially perpendicular to the planes of the clamp members to effect movement of the rods and slides toward and from the body 95 of the blank, and operating means for said guide member including provision for adjustment to vary the extent of movement of said member.

35. In apparatus of the class described, 100 clamp members relatively movable to clamp the marginal portion of a toe blank, one of said members including slides arranged to engage the surface of the blank and movable in directions toward and from the body of 105 the blank, and operating means for said slides comprising rods engaging the slides at one end, and a guide member through which said rods extend in directions inclined to the planes of the clamp members, said guide 110 member being movable in sliding engagement with the rods in directions substantially perpendicular to the planes of the clamp members to effect movement of the rods and slides toward and from the body of the blank, and means for varying the limit of movement of said guide member in the direction to move the slides away from the body of the blank.

36. In apparatus of the class described, 120 relatively movable clamp members for confining the marginal portion of a blank, one of said members including toothed portions for engaging the surface of the blank, and means for separating the blank from said toothed portions on relative movement of said members to open position.

37. In apparatus of the class described, 125 relatively movable clamp members for confining the marginal portion of a blank, one 130

of said members having toothed slides mounted thereon for engaging the surface of the blank, and stripping devices between said slides comprising yielding members arranged to project normally above the teeth on said slides.

In testimony whereof I have signed my

name to this specification in the presence of two subscribing witnesses.

IRVING W. BLANCHARD.

Witnesses:

CHESTER E. ROGERS,

LAURA M. GOODRIDGE.

Copies of this patent may be obtained for five cents each, by addressing the "Commissioner of Patents, Washington, D. C."

It is hereby certified that in Letters Patent No. 1,161,019, granted November 23, 1915, upon the application of Irving W. Blanchard, of Beverly, Massachusetts, for an improvement in "Machines for Forming Uppers of Boots and Shoes," an error appears in the printed specification requiring correction as follows: Page 5, line 97, for the word "and" read *end*; and that the said Letters Patent should be read with this correction therein that the same may conform to the record of the case in the Patent Office.

Signed and sealed this 28th day of March, A. D., 1916.

[SEAL.]

J. T. NEWTON,

Cl. 12-97.

Acting Commissioner of Patents.
